his Attorney.

UNITED STATES PATENT OFFICE.

GEORGE M. HANEY, OF GRAND RAPIDS, MICHIGAN.

SEAT AND DESK STRUCTURE.

Application filed May 1, 1920. Serial No. 378,047.

To all whom it may concern:

Be it known that I, GEORGE M. HANEY, a citizen of the United States, residing at Grand Rapids, in the county of Kent and State of Michigan, have invented new and useful Improvements in Seat and Desk Structures, of which the following is a specification.

The present invention relates to seat and desk structures; and its object is, generally, to provide an improved structure wherein a seat and a desk or table, severally adjustable, are mounted on the same support; and more particularly, to provide improved means for thus mounting and adjusting the desk or table; and further, to provide improved means for thus mounting and adjusting the seat; and, further, to provide improved means for mounting the support on a suitable pedestal.

These and any other objects hereinafter appearing are attained by, and the invention finds preferable embodiment in, the structure hereinafter particularly described and illustrated by the accompanying drawings, in which:—

Figure 1 is a side view of a structure combining a desk or table portion and a seat portion;

Figure 2 is a bottom plan view of the seat-supporting arm of the same (enlarged), showing the supporting post of the structure in horizontal section taken on line 2—2 of Figure 1;

Figure 3 is a transverse sectional view of said arm taken on line 3—3 of Figure 2;

Figure 4 is a central vertical section of said post, its pedestal, and interior parts;

Figure 5 is a horizontal sectional view of the same taken on line 5—5 of Figure 4;

Figure 6 is a vertically sectional view of certain parts taken on line 6—6 of Figure 1;

Figure 7 is a transverse sectional view of the table or desk portion taken on the supporting post's diametrical plane;

Figure 8 is a horizontally sectional view of the same taken on line 8—8 of Figure 7;

Figure 9 is a vertically sectional view of certain parts taken on line 9—9 of Figure 7; and

Figure 10 is a horizontally sectional view

of the same taken on line 10—10 of Figure 9.

In the embodiment of the invention chosen for illustration by the drawings and for detailed description in the body of this specification, a structure having a seat for the person using the desk before and a desk for the person using the seat behind (such as are commonly employed in schools and the like) is shown. A supporting hollow or tubular post 1, circular in cross section and of the same diameter throughout, is mounted on a suitable pedestal 2 provided with an upwardly extending hollow member 3, longitudinally split at 4 and adapted to be received into the lower end of the post 1. A plug 5, circular in cross section, is adapted to be driven downwardly into the upper end of the member 3 to expand the same into clamping engagement with the inner surface of the post, said plug being tapered downwardly or the bore of the member 3 being gradually enlarged upwardly, or both as shown in Figure 4, so that the plug exerts a wedging action on the member 3 to thus expand the same. The seat 6 is mounted on a supporting arm, designated generally 7, comprising lateral sections 8, 9, severally connected to the under side of the seat as by screws 10 passing through the flanges 11 of said sections. These sections are fastened together adjacent their connection to the seat, by bolts 12; and the arm is clamped to the post 1, by the bolt 13 extending through the sections intermediate the post and their connection to the seat, and by the bolt 14 on the opposite side of said post. A clearance at 15 between the portions of the sections adjacent the post 1 permits such portions to be sprung into clamping engagement with the post under the action of the bolts 13, 14. The inwardly extending spurs 16 of the sections 8, 9, are adapted to contact and preferably to bite into the post 1 in the clamping engagement of these sections therewith to more securely retain the arm 7 in its clamped position. It will be seen that the seat may be raised or lowered or turned on the post 1 to a desired position, whereupon the arm may be clamped therein as described.

The desk portion, designated generally 17, has a table 18 and a vertical portion 19. The supporting post 1 passes through the

shelf 20 of the desk portion and is adjustably clamped to said portion by the following means:

A member 21 is secured as by the screw 5 22 to the under side of the table 18 and extends downwardly into the hollow post. Means, as the threaded bolt 23 extends through this member and through the wall of the post, there being a suitable orifice 10 in one and a suitable vertically extending slot in the other for receiving this bolt; as shown, such a slot 24 is provided in said member 21 and such an orifice 25 is provided through the wall of the post. The 15 nut 26 of this bolt is prevented from turning with the bolt by the way provided by side guides 27 as particularly shown in Figures 9 and 10. The desk portion may be clamped to the post by following additional means: a stirrup 30 is provided, and located below the bolt 23, through whose ears 31 bolts 32 extend on opposite sides of the post, and through the vertical portion 19 of the table or desk portion, whereby the 25 post 1 may be clamped between the stirrup and said vertical portion. Side pieces 33 having concave surfaces 34 may be secured to the inner surface of this vertical portion to receive the arcuate surface of the post 30 as particularly shown in Figure 8. It will be seen that the desk or table portion 17 may be moved up or down or turned on the post to desired position and thereupon clamped in such position.

35 The invention being intended to be pointed out in the claims, is not to be limited to

or by details of construction of the particular embodiment thereof illustrated by the drawings or hereinbefore described.

I claim:

1. In a structure of the character described; a post; a seat; a seat-supporting arm comprising lateral sections severally connected to the seat; means adjacent the connection of said sections to the seat for fastening said sections together; means for clamping the post between said sections. 40
2. In a structure of the character described; a post; a seat; a seat-supporting arm comprising lateral sections severally connected to the seat; means adjacent the connection of said sections to the seat for fastening said sections together; means intermediate the seat and the post for clamping the post between said sections; means 50 on the opposite side of the post for clamping the post between said sections. 55
3. In a structure of the character described; a post; a seat; a seat-supporting arm comprising lateral sections severally 60 connected to the seat, at least one of said sections having an inwardly extending spur adapted to contact with the post in the assembled position of the parts; means adjacent the connection of said sections to the 65 seat for fastening said sections together; means for clamping the post between said sections.

In testimony whereof I have hereunto set my hand at Grand Rapids, Michigan, this 70 27th day of April, 1920.

GEORGE M. HANEY.
